UNITED STATES PATENT OFFICE.

LEO GREENBAUM, OF FAR ROCKAWAY, AND EDWARD VAN HOOFSTADT, OF OCEAN-SIDE, NEW YORK, ASSIGNEES TO LION MATCH COMPANY, INC., A CORPORATION OF NEW YORK.

MATCH BOOK.

Application filed February 10, 1925. Serial No. 8,129.

Our invention relates to improvements in matches, and more particularly has reference to the splints of matches such as are commonly made of paper or card and formed into match-books. The splints of such matches have heretofore been stamped out of rough stock in combs or lengths from which short pieces are separated and doubled up for making the match books. Match splints formed in this manner are unfinished in appearance, break very easily when being used, and are rough to handle, whereas according to the preferred application of our invention, the splints are toughened in the process of manufacture, are finished with a polished and round surface, and do not break as easily when being used.

In the accompanying drawings, we have illustrated in Fig. 1 in perspective, a conventional form of match-book showing matches made in accordance with our invention. Fig. 2 is a plan view illustrating one of said matches on an enlarged scale, part being broken away, Fig. 3 is a cross-section on the line 3—3 of Fig. 2, and Fig. 4 is a perspective view partly in section and parts broken away showing suitable means for forming the splints from sheets of card stock so as to embody an application of our invention.

A preferred form of mechanism for forming said match-splints is illustrated and described in co-pending patent application S. N. 686,739, and comprises a flat surface upon which a strip of paper or card from which the splints are to be made, is fed intermittently. When fed into position, a series of parallel cutters or knives, spaced apart a distance equal to the width of the splints, descends upon and cuts entirely through the paper stock, forming a series of parallel slits therein of a length equal to the length of the match splints, and at the same time or during the next operation a "comb" of said splints is severed from said strip. Then alternating splints are preferably spread oppositely out of the same plane or

staggered, to allow for grouping two or more combs in a book.

As the strip of paper or card is fed to the cutting knives, preferably the upper surface of the same is rubbed with a bar of paraffine wax, thereby laying down the fibres and imparting a gloss to the surfaces of the matches which are exposed in the book. As the knives cut through the paper or card to the under surface, they impart a slightly rounded form to the upper and exposed surface of the match-splints, slightly crowding the fibres at the sides which strengthens the splint as well as improving the appearance of the same as shown at 4. Matches produced in this manner present a strikingly improved appearance, and are preferred for their greater strength and uniformity.

Referring to Fig. 4, 5 indicates a bed plate or supporting surface, and 6 a sheet of card stock through which the parallel knives 7 have descended, cutting the same into splints. 8 indicates a suitable holder or frame for the knives and 9 a pin or other suitable means for retaining the same therein, said frame preferably having beveled sides 10 to slidably engage the block 11. The waxed upper surface of the card stock is indicated by the reference character 12.

Of course it will be understood that various modifications may be made in the construction and arrangement of parts without departing from the spirit of the invention as claimed.

We claim:—

A method of forming match splints comprising the waxing a sheet of the stock and forming cuts through said stock by supporting the stock on a bed and pressing knives toward the bed and through the stock, thereby forming splint sections which on one surface have rounded longitudinal corners.

In testimony whereof we hereunto affix our signatures.

LEO GREENBAUM.
EDWARD VAN HOOFSTADT.
